SPRAY NOZZLE

Miles Lowell Edwards, Longview, Wash.

Application June 17, 1947, Serial No. 755,099

9 Claims. (Cl. 299—118)

1

This invention relates to devices for atomizing fluids throughout a wide range of fluid flow conditions.

Specifically the invention relates to spray nozzles especially adapted for gas turbine engines, jet engines, and the like in which a vortex chamber is provided with a constantly open inlet for maintaining a spray at low fluid pressures and a ring of inlets under the control of a fluid pressure-sensitive metering device for augmenting fluid feed to the chamber whenever the pressure of the fluid increases beyond a predetermined minimum.

In the nozzles of the present invention a relatively constant atomization efficiency is maintained throughout a widely varying flow rate. This efficiency is made possible by the provision of a vortex chamber which receives streams of fluid around its circumference in centrifugally whirling condition. The streams are directed into the chamber by a ring of directing vanes receiving the fluid in thin sheet-like form from a pressure-sensitive metering device preferably in the form of a spring diaphragm. The vanes extend inward from the sharp outer inlet edges and coact to define somewhat converging tangential inlet paths around the circumference of the vortex chamber. The whirling fluid in the vortex chamber increases in rotation velocity as it is carried toward the center of the chamber. This condition creates a free vortex with a theoretical infinite number of revolutions per minute at its center. The vortex chamber discharges axially through an outlet of smaller diameter than the diameter of the chamber at its inlet. Rotative velocity is therefore high at the discharge part of the chamber, causing the formation of a fine conical spray with a relatively hollow core.

In accordance with specific embodiments of the invention the vortex chamber is provided as an insert in a casing and discharges through one axial end of the casing. The other axial end of the casing has an inlet. The ring of directing vanes preferably takes the form of a ring of teeth around the vortex chamber receiving fluid from the casing in thin sheet-like form only when a circumferentially clamped annular spring diaphragm is depressed by the fluid pressure off of its seat to open up a thin or shallow flow path to the ring of teeth. The vortex chamber preferably also has a tangential inlet receiving fluid at all times from the casing. This inlet is in advance of the ring of directing vanes and is effective to maintain a vortex flow and a fine conical spray at low fluid flow rates when the fluid is

2

not pressured sufficiently to unseat the diaphragm.

One or two vortex chambers can be used. If two such chambers are provided, the chamber receiving flow from the tangential inlet preferably discharges into the center of the second chamber receiving fluid from the directing vanes. The two chambers have concentric discharge outlets arranged in tandem relation. The inner vortex chamber is smaller than the outer chamber but is sufficient to maintain the whirling of fluid at low flow rates.

It is, then, an object of this invention to provide a spray device adapted to maintain constant atomization efficiency throughout a wide range of flow rates.

A further object of the invention is to provide a spray nozzle operative to produce relatively uniform mists from liquids at different pressures.

Another object of this invention is to provide a spray nozzle with a pressure-sensitive metering device arranged to feed fluid in thin sheets to a vortex chamber and maintain an efficient atomization of liquids at widely variant flow rates without requiring excessive liquid pressures.

A still further object of the invention is to provide a spray nozzle wherein fluid is passed in sheet form through a spring diaphragm at rates determined by pressures on the liquid, and is then caused to rotate in a vortex chamber before it is discharged in mist-like form from the chamber.

A still further object of the invention is to provide a spray nozzle having a vortex chamber inserted in a casing and arranged to receive whirling streams of fluid from a pressure-sensitive metering device in amounts determined by the pressure of the fluid.

Another object of the invention is to provide a spray nozzle having an apertured spring diaphragm receiving a vortex chamber in the aperture thereof and supplying metered amounts of fluid into said chamber through a ring of circumferentially spaced directing vanes.

Other and further objects of the invention will be apparent to those skilled in the art from the following detailed description of the annexed sheets of drawings which, by way of preferred examples, illustrate two embodiments of the invention.

On the drawings:

Figure 1 is a top plan view of an inlet end of a spray nozzle according to this invention.

Figure 2 is a plan view of the discharge end 55 of the nozzle.

Figure 3 is a cross-sectional view, on an enlarged scale, taken along the line III—III of Figure 1.

Figure 4 is a transverse cross-sectional view, on a reduced scale, taken along the line IV—IV of Figure 3.

Figure 5 is a transverse cross-sectional view taken along the line V—V of Figure 3.

Figure 6 is a transverse cross-sectional view taken along the line VI—VI of Figure 3.

Figure 7 is an axial cross-sectional view of a modified embodiment of the spray nozzle of this invention.

As shown on the drawings:

The nozzle 10 of Figures 1 to 6 includes a hollow cylindrical open-ended casing 11 with an internal shoulder 11a at one end thereof defining a reduced diameter open end 11b and with internal threads 11c at the other end thereof.

A gasket 12 is bottomed on the internal shoulder 11a of the casing 11.

A nozzle member 13 is mounted in the casing 11 and has a central frusto-conical portion 13a projecting freely through the opening 11b of the casing together with a peripheral ring flange 13b bottomed on the gasket 12. A cylindrical portion 13c of the member 13 projects above the flange 13b in the central portion of the casing to terminate at a flat rim 13d. A cylindrical bore 13e extends inwardly from the rim 13d axially of the member 13 to a rounded converging bore 13f extending through the end of the frusto-conical portion 13a.

A ring 14 preferably composed of rigid material such as metal is bottomed on the ring flange 13b of the member 13 in the casing 11 and is spaced concentrically from the portion 13c of the member 13 to provide an annular localized chamber 15 in the casing surrounding the portion 13c.

A spring diaphragm 16 preferably composed of a plurality of stacked spring metal disks 16a, 16b, and 16c, is bottomed on the ring 14 and projects inwardly to surround the portion 13c of the member 13. The spring diaphragm thus has an aperture 16d surrounding the cylindrical portion 13c of the member 13.

A disk member 17 has a ring flange 17a bottomed on the spring diaphragm 16 and coacting with the ring 14 to clamp the outer peripheral portions of the spring metal disks therebetween. The ring flange 17a has a ring of holes 17b therearound communicating with the inner peripheral portion of the diaphragm 16.

The ring member 17 has a central portion with a cylindrical bore 17c extending from a flat rim 17d aligned with the rim 13d to a closed top wall 17e. The rim 17d has a ring of teeth or directing vanes 18 thereon bottomed on the rim 13d. This ring of vanes 18 can be formed integral with the rim 17d by a milling operation, or can be secured to the rim 17d by welding, brazing, or the like. Alternately, of course, the vanes could be formed on or affixed to the rim 13d. The teeth or vanes 18 are circumferentially spaced and define flow paths 19 therebetween. These flow paths communicate at their outer ends with the aperture 16d of the diaphragm 16 and with the chamber 15. The inner ends of the paths 19 communicate with a vortex chamber 20 provided by the bores 13e and 17c of the members 13 and 17. These bores are aligned to cooperate in closing a cylindrical chamber 20 having a reduced diameter axial outlet 21 defined by the wall 13f. The top 17e of the member 17 closes the top of the chamber 20.

The rim 17d of the member 17 projects radially beyond the teeth or vanes 18 to provide a valve seat 22 for the top face of the spring diaphragm 16 around the entire aperture 16d of the diaphragm. The diaphragm is slightly deflected as shown in Figure 3 to have sealing engagement with the valve seat 22 and is adapted to be unseated upon application of further deflecting pressure thereon to open the flow paths 19 and the chamber 15 to the holes 17b, thereby permitting flow between the seat 22 and top wall of the diaphragm to the paths 19. The flow path past the seat 22 is shallow or thin and the fluid will be forced to assume a thin sheet-like form. The path increases in depth or thickness as increased fluid pressure further deflects the diaphragm.

The member 17 has a hole 23 drilled through its side wall immediately under the top end wall 17e. This hole 23 extends tangentially into the chamber 20 as best shown in Figure 4 and preferably has an outwardly flared or beveled inlet mouth 23a. Fluid flowing through the inlet 23 is directed circumferentially around the cylindrical chamber 20.

As shown in Figure 6, fluid entering the chamber 20 through the flow paths 19 between the vanes 18 is also directed in a circumferential path in the same direction as fluid from the tangential inlet 23. The vanes 18 have sharp outer ends 18a so that the entrance mouths to the flow paths form a relatively open continuous circle. The back walls 18b of the vanes diverge from the front walls 18c so that the vanes are relatively thick at their inner ends 18d and the discharge ends of the flow paths 19 are narrower than the inlet ends thereof. The paths are non-radial to direct the fluid circumferentially into the chamber 20 as shown.

As best shown in Figure 3, a sleeve 24 is mounted in the casing on the ring portion 17a of the member 17. The sleeve 24 snugly fits in the casing and has an internal shoulder 24a spaced above the member 17. A fine woven strainer wire 25 spans the top end of the sleeve and is bottomed against the shoulder 24a. This wire is backed with a coarse woven wire support 26. A ring 27 is pressed in the sleeve 24 to clamp the wire screens 25 and 26 against the shoulder 24a and hold the same in tight condition.

A rubber packing ring R is bottomed on the sleeve 24.

A nipple 28 is threaded into the threaded portion 11c of the casing 11 and has a recess 28a in its end face receiving the rubber ring R. The nipple 28 has a threaded port 28b for attachment to a pipe or the like. The nipple 28, as shown in Figure 1, preferably has a square head portion 28c that can be readily engaged by a wrench to thread the nipple tightly against the ring R for coacting with the casing shoulder 11a to clamp together the sleeve 24, the member 17, the ring 14, and the member 13. The slots or grooves 17d of the casing can receive a spanner wrench to hold the casing against rotation.

In operation of the spray nozzle 10 fluid enters through the nipple 28 and is filtered through the screens 25 and 26 from which it can flow through the holes 17b against the diaphragm 16. The diaphragm is tightly seated against the seat 22 unless the fluid pressure is sufficient to deflect it off of the seat. The diaphragm can have any desired resistance and is conveniently made up of a plurality of spring plates which can be substituted to produce the desired load on the seat. When the diaphragm is closed on its seat

no fluid can flow through the paths 19 and the entire fluid flow will be through the tangential inlet 23 into the vortex chamber 20. The fluid will whirl in this chamber and be ejected through the discharge 21 in a fine conical shaped mist. When the fluid pressure increases sufficiently to unseat the diaphragm off of the seat 22, the fluid then flows in a thin, sheet-like flow path between the diaphragm and the seat into the flow paths 19. The vanes defining these paths direct the flow as illustrated in Figure 6 so that the thin sheet of fluid is broken up into a plurality of whirling streams rotating in the same direction as the stream from the tangential inlet 23. These streams whirl around the vortex chamber 20 and commingle with the stream from the tangential inlet 23 to discharge together in fine mist-like form through the outlet 21.

In some installations the inlet 23 may be eliminated. It is provided for creating a spray at very low fluid pressures, and, of course, this spray only has a very low flow rate. When the pressures are increased to open up the diaphragm, the flow rate of the spray is materially increased as the pressures of the fluid further deflect the diaphragm. It should be understood, however, that materially enhanced pressures are not necessary since the flow rate will increase substantially as the diaphragm deflects to permit thickening of the sheet of fluid between the seat 22 and the diaphragm. The directing vanes are interposed between the thin sheet-like flow path and the point of vortexing the fluid in the chamber 20.

The modified device 30 shown in Figure 7 has parts substantially identical with parts described in connection with Figures 1 to 6 marked with the same reference numerals.

In Figure 7 a disk 31 is bottomed on the gasket 12 and has an upstanding cylindrical portion 31a radially inward from the ring 14. This portion 31a has a flat rim 31b on which the ring of directing vanes 32 is provided. As explained above, these vanes can be milled into the rim, or can be affixed thereto, as by brazing, welding, or the like. Flow paths 33 such as the paths 19 described hereinabove are provided between the vanes 32. The member 31 has a cylindrical bore 31c extending downwardly from the rim 31a to a rounded converging bore or wall 31d. The cylindrical bore 31c defines a vortex chamber 34 with a reduced diameter outlet 35 aligned with the gasket 12.

A disk member 36 is bottomed on the diaphragm 16 and has a ring of holes 36a therethrough communicating with the top of the diaphragm. The central portion of this disk 36 has a depending frusto-conical portion 36b and an upstanding cylindrical portion 36c. The portions cooperate to define a second vortex chamber 37 with a tapered outlet 38 at the bottom thereof converging to a reduced-diameter discharge opening 39 in the axial central portion of the wall 31d of the member 31. The top of the chamber is closed by a disk 39 which can be welded or otherwise affixed thereto. A tangential inlet 40 is provided in the portion 36c of the ring 36 immediately under the closure wall 39.

The device of Figure 7, therefore, has two vortex chambers 34 and 37, with the chamber 37 having an outlet 39 concentric with the outlet 35 of the chamber 34 and communicating therewith in advance of the final discharge end of the outlet 35.

The concentric openings for the two vortex

chambers provide for the merging of the sprays from both chambers. The modification of the multi-chamber arrangement makes possible the use of a smaller vortex chamber for the single tangential inlet. This chamber is sufficient to create a high speed rotation or vortexing at very low rates of flow. The main vortex chamber partially surrounding the small chamber is provided for accommodating high flow rates and to sufficiently whirl or vortex the streams from the flow paths 33. As in the embodiment of Figures 1 to 6, the flow paths 33 receive the fluid in thin, sheet-like form determined by the spacing of the diaphragm from its seat 22.

From the above descriptions it will be understood that the invention provides spray nozzle arrangements which create fine mists throughout a wide range of flow determined by pressure of the fluid being sprayed. The flow rates increase as desired with an increase of pressure on the fluid, and it is not necessary that excessive pressures be maintained for obtaining high flow rates. The fluid is caused to flow in thin, sheet-like form between a fixed seat or wall and a movable coacting diaphragm or cooperating wall under the influence of pressure on the fluid. The thin sheet of fluid is then directed by a ring of vanes which cause the fluid to rotate in a single direction. The rotating fluid is introduced into a cylindrical chamber having a reduced axial outlet and is vortexed in this chamber so that the fluid will discharge in fine mist-like form out of the axial outlet. In order to maintain a spray at very low fluid pressures, the vortexing chamber can be equipped with a tangential inlet that is open at all times. However, the main flow of fluid is past the deflectable pressure-sensitive metering device.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A spray device comprising a casing, a member carried by said casing and defining a vortex chamber, a ring of circumferentially spaced directing vanes surrounding said vortex chamber and defining fluid flow paths for introducing fluid in whirling streams into said chamber, means in said casing for metering fluid in thin sheet form to the outer ends of said ring of vanes, said means being deflectable under pressure of fluid in the casing to increase the thickness of the sheet of fluid flowing to the outer ends of the vanes, said casing having an inlet at one end thereof and an outlet at the other end thereof receiving fluid from the vortex chamber therein, and a tangential inlet for said vortex chamber positioned in said casing between said pressure-sensitive deflectable means and said casing inlet.

2. A spray nozzle comprising a hollow open ended casing having an internal shoulder at one end thereof and an internal threaded portion at the other end thereof, a spray member bottomed on said shoulder and defining a vortex chamber with a reduced diameter outlet discharging through the shouldered end of the casing, a ring of circumferentially spaced directing vanes surrounding said vortex chamber and arranged to direct streams of fluid from said casing into said chamber in circumferentially whirling paths, a valve seat located adjacent the outer ends of the vanes, a flexible pressure-responsive annular di-

aphragm in said casing having an inner margin arranged to cooperate with said valve seat to meter fluid in variable thin sheet form to said vanes, circular members in said casing clamping the outer peripheral portions of said diaphragm therebetween and affording space for pressure flexing of the inner portion of the diaphragm, a sleeve in said casing bottomed on one of said circular members and carrying filter screens spanning the interior of the casing, and a nipple threaded into the threaded end of said casing bottomed on said sleeve and coacting with the shoulder of the casing to clamp all of the parts in position in the casing.

3. A spray device comprising a hollow open ended casing having an internal shoulder at one end thereof and an internally threaded portion on the other end thereof, a first member in said casing bottomed on said shoulder and having an open topped cylindrical chamber with a converging reduced diameter axial outlet at the bottom thereof, a second member in said casing defining a closed topped open bottomed cylindrical chamber coaxial with the chamber defined by said first member, a ring of circumferentially spaced vanes between said first and second members defining non-radial flow paths into the chambers provided by said members, a deflectable spring annulus surrounding said ring of vanes and coacting with said second member to define a pressure sensitive flow path to the outer ends of said vanes for directing fluid in thin sheet form into said non-radial flow paths and thence into said chambers, filter means in said casing, and a nipple threaded into the threaded end of said casing for holding all of the parts in the casing in clamped relation with the internal shoulder.

4. A spray device capable of discharging fluid in fine mist-like form throughout a wide range of flow rates which comprises means defining a vortex chamber with a reduced diameter outlet at one end thereof and a continuously open tangential inlet at the other end thereof, a ring of circumferentially spaced directing vanes surrounding said chamber between said tangential inlet and said outlet, said vanes having sharp outer ends to provide a substantially continuous annular entrance mouth to said chamber, said vanes increasing in thickness inwardly from said sharp outer ends to provide converging flow paths from said entrance mouth into said chamber, and said flow paths being non-radial for introducing fluid to whirl in the chamber in the same direction as fluid introduced through said tangential inlet.

5. A spray device comprising a casing, an insert in said casing defining a cylindrical vortex chamber having a reduced diameter outlet discharging through one end of said casing, said chamber having an inlet in the side wall thereof remote from said outlet and arranged for directing fluid in the casing into the chamber in a non-radial stream for whirling the fluid, a ring of flow-directing vanes arranged for directing fluid in whirling streams into the chamber between said inlet and said outlet, and a pressure-sensitive fluid metering device in said casing between said inlet and said vanes to control added fluid flow to said chamber and comprising annularly arranged opposed relatively separable surfaces.

6. A spray nozzle comprising a casing, means in said casing defining a localized vortex chamber with an axial outlet at one end of the casing, means for introducing fluid into the other end of said casing around said localized vortex

chamber, a pressure-sensitive diaphragm in said casing arranged for supplying fluid in thin sheet form into said localized chamber, and directing vanes receiving said fluid in thin sheet form thereagainst to introduce the fluid in whirling stream form around the circumference of said chamber.

7. A spray device comprising a casing, a member in said casing defining a first vortex chamber having a reduced-diameter outlet discharging through one end of the casing, a second member in said casing defining a second vortex chamber having an outlet concentric with and lying within the outlet of said first vortex chamber, a ring of circumferentially spaced directing vanes in said casing arranged for introducing fluid into said first chamber, a deflectable spring annulus in said casing arranged for metering fluid in thin sheet form to said directing vanes, and said second member having an opening joining said casing and said second vortex chamber in advance of said annulus for introducing a stream into said second chamber to whirl therein in the same direction as the streams by said directing vanes whereby the whirling stream from the second vortex chamber will discharge into the whirling streams from the first chamber for simultaneous discharge out of the casing.

8. In combination in a spray nozzle construction, a spray discharge assembly including means defining a vortex chamber, said means including an annular series of angularly disposed flow paths directed transversely into the vortex chamber, means defining a casing enclosing said vortex chamber means and having an inlet for fluid under pressure, said vortex chamber means including an annular shoulder outside of said chamber and disposed adjacent the outer ends of an at the upstream side of said flow paths and facing downstream and an annular flexible control diaphragm having its inner margin bearing in fluid-checking relation against said shoulder and blocking flow of the pressure fluid from within the casing into said vortex chamber through said flow paths, the outer margin of said diaphragm being mounted in fixed relation within the casing means and with the inner margin biased against said shoulder, said inner margin of the diaphragm being flexible away from said shoulder under predetermined fluid pressure to a fluid passage spacing with respect to said shoulder proportionate to the fluid pressure, whereby to control the pressure fluid supply through said flow paths in sheet-like form.

9. In combination in a spray nozzle construction, a spray discharge assembly including means defining a vortex chamber, said means including an annular series of angularly disposed flow paths directed transversely into the vortex chamber, means defining a casing enclosing said vortex chamber means and having an inlet for fluid under pressure, said vortex chamber means including an annular shoulder outside of said chamber and disposed adjacent the outer ends of and at the upstream side of said flow paths and facing downstream, and an annular member having its inner margin bearing in fluid-checking relation against said shoulder and blocking flow of the pressure fluid from within the casing into said vortex chamber through said flow paths, the outer margin of said member being held in position within the casing means and the inner margin being biased against said shoulder, said inner margin of the member being movable away from said shoulder under predetermined fluid pres-

sure to a fluid passage spacing with respect to said shoulder proportionate to the fluid pressure, whereby to control the pressure fluid supply through said flow paths in sheet-like form.
